UNITED STATES PATENT OFFICE.

LEWIS A. MOLOGNE, OF SMITHTON, PENNSYLVANIA.

WINDOW LOCK.

Application filed May 20, 1922. Serial No. 562,367.

To all whom it may concern:

Be it known that I, LEWIS A. MOLOGNE, a citizen of the United States, residing at Smithton, in the county of Westmoreland 5 and State of Pennsylvania, have invented certain new and useful Improvements in Window Locks, of which the following is a specification, reference being had to the accompanying drawings.

10 This invention relates to window locks and has for its object to provide a device of this character capable of being applied to any type of window without marring the window by the use of screws or like fastening means.

Another object of the invention is to provide a device of this character capable of being readily attached to any portion of the sash if desired for holding both the upper 20 and lower sashes in various positions relative to each other.

A further object of the invention is to provide a lock of this character including an adjustable bracket adapted to be positioned 25 at any point longitudinally of either vertical rail of a sash, the bracket being adapted to support a member arranged to engage both sashes to prevent movement of said sashes in the usual manner beyond a certain 30 point predetermined by the adjustment of the bracket on the sash.

With these and other objects in view, the invention consists in the improved construction and arrangement of parts to be hereininafter more particularly described, fully claimed and illustrated in the accompanying drawings, in which:—

Figure 1 is a fragmentary longitudinal sectional view of a window frame showing the 40 invention applied;

Figure 2 is a fragmentary top plan sectional view of the window casing showing the position of the lock on the rail of the window;

45 Figure 3 is a perspective view of the bracket with the wedge member and fastening means removed; and

Figure 4 is a perspective view of the wedge member.

50 Referring to the drawings, 5 designates a bracket comprising arms 7 and 8, the arm 7 being stepped longitudinally thereof. The end portion 9 of the arm is adapted to engage a portion of the window, while the 55 end portion 10 is provided with an elongated slot for the purpose of adjustment. The in-

termediate portion 11 of the arm 7 is provided with a bearing opening 12, the purpose of which will be hereinafter described.

The arm 8 of the bracket is substantially 60 L-shaped, the end portion 13 of the arm having an elongated opening 14 adapted at times to register with the portions of the opening in the end portion 10 of the arm 7, a bolt 16 being passed through said registering openings to hold said arms in their adjusted positions. The end portion 17 of the arm 5 is provided with a bearing opening 18 adjacent the junction of the end portion 17 with the end portion 13, the opening 18 substantially registering with the opening 12 of the arm 7 for the reception of a bolt or shaft 19, the bolt being provided with a nut 20 to properly hold the bolt in accordance with the adjusted positions of the arms 7 70 and 8. The nut 20 of the bolt 19 may also be used to adjust the arms 7 and 8, in view of the fact that when said nut is rotated in one direction the arms 7 and 8 are moved toward each other as the head of the bolt engages the intermediate portion 11 of the arm 7.

To permit a further range of adjustment a plate 21 is provided, said plate having its longitudinal edges 22 extended outwardly at right angles to the plate to provide guides between which the end portion 17 of the arm 8 is slidable, one end portion of the plate 21 having an elongated opening 23 adapted to receive the bolt 19 and also to register with the opening 18. The end portion 10 or intermediate portion 11 of the arm 7 substantially cooperates with the end portion 13 of the arm 8 to provide a compartment adapted to receive a wedge member 24, said wedge member having an opening adapted to receive the portion of the bolt disposed within the compartment. It is of course obvious that the compartment provided in the arm may be adjusted according to the width of the rails of the sash. In the formation of the wedge member, the face 25 is beveled from a point inwardly of the upper end 26 of the wedge, the opposite face 27 of the wedge being straight. The purpose of this 90 is to permit a proper locking action by causing a portion of the face 25 to engage the window sash and at the same time permit the flat face 27 to engage the sash longitudinally of said face. By this means the wedge member is firmly lodged between the sashes.

100 This arrangement also permits the wedge 110

member to readily enter the space between the sashes.

In the application of the device, the arms 7 and 8 are adjusted toward or away from each other as the case may be according to the width of the vertical rails of the sash. When the bolt 19 has been adjusted according to the width of the rail, the bolt 16 is operated to secure the arms in their adjusted positions. It is of course obvious that the bracket 5 may be positioned at any point longitudinally of the vertical rail of the upper sash and in engagement with the inner face of said rail so as to position the point of the wedge toward the lower sash. By this means, upon movement of the upper sash, or vice versa, the extent of said movement will be limited, according to the position of the bracket on the rail of the upper sash. This permits the upper sash to be lowered a certain distance and the lower sash to be raised a certain distance, for proper ventilation, without danger of either sash being moved to a position to permit entrance of a person or to permit the bracket to be reached by a person from the outside. If it is not desired to use a lock to hold the windows in position for ventilation, the bracket may again be adjusted toward the lower rail of the upper sash so as to provide a lock for holding both of said sashes in their closed positions, movement of either sash being positively prevented.

From the foregoing it will be readily seen that this invention provides a novel form of window lock capable of being applied to any window sash without the use of nails, screws or like fastening means, and also capable of being used in connection with windows regardless of whether they fit the window casting or not, and regardless of the weather, as the lock does not depend on the windows fitting properly in the casing for its effi-

cient operation, and all of these features are possessed by a device composed of only a small number of simple parts.

What is claimed is:—

1. A window lock comprising a pair of arms adjustably connected at one of their corresponding ends for movement toward or away from each other and adapted to embrace a rail of a window sash, means for securing said arms in their adjusted positions relative to each other, a bolt extending between and engaging said arms, a wedge member mounted on the bolt between said arms, and an adjusting nut carried by said bolt, said arms being movable toward each other upon rotation of the nut on the bolt.

2. A window lock comprising a pair of arms adapted to engage a rail of a window sash, each arm having one end thereof extended in angular relation, corresponding ends of said arms having registering openings, fastening means disposed in said openings for holding the arms in various adjusted positions, a bolt extending between and engaged with said arms, a wedge member carried by the bolt, and an adjustable plate mounted on one end portion of the bolt and engaged with the opposite end portion of one of said arms.

3. In combination with the upper and lower sashes of a window, a bracket comprising a pair of adjustably connected arms, a bolt extending between and engaging said arms, said bolt being adapted to urge the ends of the arms in engagement with a portion of the upper sash, a wedge member carried by said bolt, said wedge member being arranged to extend between and engage the confronting faces of the rails of said upper and lower sashes.

In testimony whereof I hereunto affix my signature.

LEWIS A. MOLOGNE.
